UNITED STATES PATENT OFFICE.

MARION H. COMPTON, OF MUSCATINE, IOWA.

ACETYLENE-GAS GENERATOR.

Application filed August 3, 1921. Serial No. 489,586.

To all whom it may concern:

Be it known that I, MARION H. COMPTON, a citizen of the United States, residing at Muscatine, in the county of Muscatine and State of Iowa, have invented certain new and useful Improvements in Acetylene-Gas Generators, of which the following is a specification, reference being had to the accompanying drawings.

10 This invention relates to acetylene gas generators of that type known as pit plants wherein a container or casing is provided sunken in the ground to avoid freezing and having water in its lower end, with a gas bell disposed above the water and a carbide receptacle contained within the gas bell and operated by the gas bell to cause the discharge of carbide into the water in the lower end of the container.

20 One of the objects of this invention is to provide an outer casing whose lower end constitutes a chamber containing water, this casing having its lower end formed to provide a relatively deep inverted cone so that 25 the sludge or carbide from which gas has been generated will collect in the extreme lower end of the casing, the generator being so constructed that at intervals the gas bell and the carbide holder may be removed from 30 the casing and a pipe inserted downward through the upper end of the casing to the extreme lower end of said tapered bottom which will make possible the pumping off or 35 withdrawal of the refuse matter or residue without inconvenience and without the necessity of withdrawing the water in the lower end of the casing or tank.

40 Another object of the invention is to provide an outer casing having its lower end sharply tapering downward, or in other words being in the form of a deep inverted cone, so that in installing the machine in a pit in the ground with its top even with or a trifle below the surface of the ground, the 45 cone-shaped bottom shall provide an easy manner of leveling up the machine, this cone-shaped bottom further acting under the weight of the water within the machine, which is approximately about 200 gallons, to cause said machine to settle after being placed in the pit and cause said machine to settle in a perpendicular position and retain the machine in the same vertical position as when installed.

Other objects will appear in the course of 55 the following description.

My invention is illustrated in the accompanying drawings, wherein:—

The figure is a vertical sectional view of 60 an acetylene gas generator constructed in accordance with my invention.

Referring to these drawings, 10 designates the outer casing of the generator, which may be of any desired length and diameter, and supported in any suitable 65 manner, the lower end of this casing being downwardly tapered or having the form of an inverted cone, as at 11. Above the tapered lower end of the casing there is provided an upwardly and inwardly extending 70 flange 12 which is riveted or otherwise attached to the wall of the casing and the top of the casing is closed by a removable cap or cover 13.

Disposed within the upper portion of the 75 casing 10 above the water therein and resting upon the flange 12 is a pedestal 14 outwardly flared at its lower end, as at 15, to rest upon the flange 12. The pedestal at its 80 upper end is double walled so that an annular sealing space 17 is formed between the outer wall 16 and the inner wall of the pedestal, this sealing space being filled with water and above the level of the water the sealing space has perforations 18. 19 designates a gas bell of usual form with its lower portion disposed within the sealing compartment 17. The perforations 18 permit gas to pass from the interior of the pedestal to the interior of the bell. The bell has a 90 handle 20 whereby it may be raised.

Supported on the pedestal 14 is a carbide container 21, the lower end being hopper-shaped at 22. The upper end of the hopper-shaped bottom is channeled to seat upon the upper edge of the inner wall of the pedestal 14. A laterally extending chute 23 extends from the lower end of the hopper 22. The discharge through this chute is controlled by a valve 25. Any other suitable valve may be used, however. The valve is pivoted and provided with an arm 30 extending upward to a lever 33 disposed within the housing 31 and mounted upon a supporting bar 32. The lever is pivoted at 34 and is pivoted adjacent its outer end to the extremity of the arm 30. The lever at its other end is pivotally connected to a vertically ex-

tending rod 36 which terminates in a tapered extremity disposed just above the opening from the hoppers. A weight 37 is carried on the end of the lever.

5 If the gas in the bell is reduced, the gas bell falls, strikes the upper end of the rod 36, raises the outer end of the lever 33, and this opens the valve 25, allowing the discharge of carbide. As soon as sufficient gas 10 has formed as to cause the raising and lifting of the bell, the bell will lift and the weight 37 will cause the parts to return to their normal positions. The rod 36 also acts to break up the carbide in the lower end of 15 the container.

A reserve carbide container 38 is disposed within the upper end of the hopper and is normally closed by a valve 39. The valve is held closed by a latch 40 on the lower end of the lever 41, the upper end of the lever extending into the path of movement of the top of the gas bell. Thus if the gas bell should continue to lower after it has struck rod 36, the gas bell will eventually strike the upper end of the lever or rod 41, tilt this rod, and thus withdraw the latch from underneath the valve 39 and the valve will drop, permitting the reserve supply of carbide to be discharged into the container. The gas discharge pipe 42 has its lower end extending into the water contained in the lower portion of the casing 10. The upper end of this pipe is closed by a cap and has a branch 43 extending out from the casing, and disposed in the length of this pipe 42 is a filter. Connected to the lower end of the pipe 42 is a branch 45 which extends upward into position just below the hopper-shaped portion 22 of the carbide container and is bent to form an inlet terminal 46. The gas within the gas bell will be discharged out through this inlet terminal 46 through the pipes 42 and 43.

45 The acetylene gas generating mechanism which is disposed within the bell and the particular construction of the bell itself forms the subject-matter of a separate application for patent filed on the 9th day of December, 1922, Serial No. 605,854, which is a division of the present application, this invention relating merely to the shape of the casing 10 and the manner in which this casing 10 operates. The general operation of the carbide feeding mechanism will be understood from what has gone before.

50 There are two very important advantages in a casing such as the casing 10 formed with the very sharply conical lower end 11, which lower end entirely terminates at the apex of the cone 11.

55 If it be desired to clean or repair the parts, it is only necessary to take off the cap 13, entirely remove the gas bell 19, and then remove the carbide container, which will

leave the pedestal resting upon the flange 12. It is not necessary ordinarily to remove the pedestal 14 nor to withdraw the water within the sealing space 17. When sludge is to be removed, then a pipe is inserted downward through the casing so the lower end of the pipe is adjacent the lower extremity of the tapered portion 11 of the outer casing and the sludge may be withdrawn without withdrawing the water within the lower end of the casing and without disturbing this water and causing the suspension of sludge particles therein. Of course, if it is desired to remove the pedestal also, this can be readily done by lifting it off of its engagement with the flange 12. By reason of the slightly different angles of the flared portion 15 and of the flange 12, a wedging engagement is secured between this flange 15 and the flange 12 which will secure a very tight joint between the pedestal and the flange 12 and at the same time this joint being disposed below the water line it is water-sealed.

50 A very important advantage secured by the inverted cone-shaped bottom or lower end of the outer casing is that in installing the machine in a pit the cone-shaped bottom provides a convenient and easy method of leveling said machine. In other words, if the lower end of the outer casing were relatively flat it would be obviously difficult to so place the casing that its axis was truly vertical, and it is obvious that in order for the machine to work properly that its axis should be truly vertical. With the cone-shaped bottom, however, the casing rests upon the tip of the cone-shaped bottom as upon a pivot and may be rocked in one direction or the other until the axis of the casing is truly vertical. Furthermore, when the machine is installed the weight of the water in the generator chamber, that is in the outer casing, causes the casing to settle and this conical bottom causes the machine to settle vertically and acts to retain the machine in its vertical position, plumb and level, as when installed. This cannot be obtained by a casing whose bottom is flat or only slightly conical. It will be seen that this sharply conical bottom is not only necessary in order that the outer casing of the generator shall be readily set in position and readily rendered vertical, but it is also necessary in order that the sludge shall accumulate at the lowest possible portion of the bottom and, therefore, be removable through a pipe. If the bottom was a shallow cone, this sludge would not tend to settle in such a concentrated form at the axial center of the machine as would permit its removal through a pipe without such a disturbance of the sludge as would render it necessary to practically entirely remove all of the 100

water from the generator. With my construction only a very small portion of the water is removed with the sludge, thus doing away with the necessity of entirely removing all of the water, which is one of the great objections to the ordinary acetylene gas generator, and, of course, this does away with the necessity of filling up the generator again with water.

10 I claim:—

A gas generator including an outer metallic casing constituting a closed container

and adapted to be embedded in the ground, the lower end of the outer casing being downwardly tapered to form a relatively 15 deep, inverted, acutely pointed cone whereby to facilitate the embedding and installing of the casing and the removal of sludge, the casing terminating at the extreme apex of the cone, and gas generating mechanism disposed within the casing.

In testimony whereof I hereunto affix my signature.

MARION H. COMPTON.
